UNITED STATES PATENT OFFICE

JOHN BLISS, OF LONDON, ENGLAND, ASSIGNOR TO C. C. WAKEFIELD & COMPANY, LIMITED, OF LONDON, ENGLAND, A BRITISH COMPANY

LUBRICATING DEVICE

Application filed September 8, 1928, Serial No. 304,742, and in Great Britain November 30, 1927.

This invention consists in improvements in or relating to lubricating devices particularly for use with steam locomotives and other steam engines and of the type consisting of a chamber for containing the lubricant and another chamber communicating therewith in which steam from the boiler is admitted and in which it is condensed. The resulting water derived from condensation passes down into the lubricant container and the lubricant is floated on the water and is propelled thereby through lubricant jets. The latter communicate with conduits leading to the various portions to be lubricated, and the lubricant is expelled from the conduits by means of steam admitted thereto. Also, in the type of lubricating device to which this invention relates, two independent valves are provided to control the apparatus, i. e. a main steam-inlet control valve for admitting the steam to the condensing chamber, and a lubricant control valve for controlling the flow of lubricant to the jets. These two valves have hitherto been independently operable and it frequently happens that the attendant will close the main steam valve and leave the lubricant valve unclosed when the engine is not running, with a consequent waste of lubricant.

An object of the present invention is to overcome this difficulty, and in lubricating apparatus of the type above described having two independent valves, there is provided, according to the present invention, a single valve-operating member in combination with means coupling it with both the steam-inlet control valve and the lubricant control valve whereby both valves are actuated by said single operating member. The parts are preferably so constructed that as the operating member is moved to open the valves, the steam-inlet control valve will be opened prior to the opening of the lubricant control valve so that, by this means, at the commencement of operations, the requisite amount of steam may be allowed to condense in the condensing chamber before it is required to begin lubrication.

In one example of the invention, the steam-inlet control valve comprises a main

valve portion in association with a jockey valve, and means is interposed between the valve-operating member and the steam-inlet control valve whereby the jockey valve is first opened during the initial movement of the valve-operating member, and a further movement of the latter serves to open also the main steam valve portion and the lubricant control valve.

In order that the invention may be more clearly understood, one preferred construction will now be described, as an example only, with the aid of the accompanying drawings, in which—

Figure 1 is a sectional elevation taken through the steam-condensing and lubricant-containing chambers on the line 1—1 of Figure 2;

Figure 2 is a section on the line 2—2 of Figure 1;

Figure 3 is a section on the line 3—3 of Figure 1, and

Figure 4 is a plan view of the apparatus shown in Figure 1.

Like reference numerals indicate like parts in the several figures of the drawings.

The lubricating apparatus shown is of well-known construction, and, briefly, comprises a steam-condensing chamber 10 at the upper end of the apparatus, and a lubricant-containing chamber 11 beneath it. Water condensed from steam admitted to the chamber 10 passes by means of a conduit 12 past a non-return valve 13 and a manually-operable valve 14 to a passage 15 formed in a core portion 16 extending through the lubricant chamber 11.

The lubricant, which is floated on the water admitted through the passage 15, enters at 17 another passage 18 formed in the core portion 16 and passes from the lower end of the passage 18 to a rotary plug valve 19, which is shown in the drawings in its closed position. The valve 19 has in it an axial passage 20 with which communicates a transverse passage 21, which can be brought into and out from register with the lower end of the conduit 18. A second transverse passage 22, which also communicates with the passage 20 and is arranged at right-

angles to the passage 21, serves to connect the passage 20 with another passage 23 (Figure 1) leading to the lubricant jets 24. It will be seen, from a consideration of the drawings, that when the valve passage 21 is closed to the passage 18, the passage 22 is also closed to the passage 23, and vice versa.

The communication between the passage 23 and each of the lubricant jets 24 is controlled by the valve 25, and all the valves 25 can be manually adjusted. The jets 24 discharge upwardly into passages 26 and, as will be seen in Figure 3, these passages, at their upper end, are bent over horizontally and in the horizontal portion they each communicate with another passage 27, into which steam is admitted in a manner to be described later. The oil is discharged from the horizontal portion of the passages 26 into conduits 28 leading respectively to the parts to be lubricated.

In accordance with the present invention, steam is led from the boiler to the chamber 10 through a conduit 30, and the passage of the steam is controlled by means of a main valve 31 and a jockey valve 32 seated within an axial passage formed in the main valve portion 31. A transverse rock-shaft 33 situated below the valve 31, 32 has secured to it a main operating handle 34 by which it can be rocked. On the rock-shaft and beneath the valve is fixed a cam 35 so shaped that the first portion of its movement will raise the jockey valve 32 from its seating in the main valve, and a further movement will cause both the jockey valve 32 and the main valve portion 31 to be raised together. The flow of steam past the jockey valve, when that alone is raised, is relatively restricted, whereas when both the jockey valve and the main valve portion are open, a relatively unrestricted flow of steam occurs into the chamber 10.

Secured to the spindle of the valve 19 is a crank-arm 36, and interconnecting the main operating member 34 and the crank-arm 36 is a link member 37 pivotally connected to both the operating member and the crank-arm.

The construction and arrangement of the parts is such that during the first movement of the main operating member 34, which will result in raising the jockey valve 32 only from its seat, the corresponding turning movement imparted through the link 37 and crank-arm 36 to the valve 19 will not turn the valve sufficiently to establish communication between the passage 22 in the valve and the passage 23 leading to the lubricant jets, so that although the jockey valve is opened to admit steam to the chamber 10, the flow of lubricant to the jets 24 is still shut off. When, however, the main operating member is moved further so that the cam 35 raises both the jockey valve 32 and the main valve mem-

ber 31, the valve 19 opens communication between the passages 18 and 21 and the passages 22 and 23 respectively.

It will be seen that the valve 31, 32 controls the admission of steam to the passages 27, and the steam passing down these passages into the horizontal portions of the passages 26 serves to force oil into the parts to be lubricated.

It will be appreciated that not only does the admission of steam to the apparatus enable requisite condensation of the steam to occur, but it also is used to warm up the lubricator as a whole.

It will therefore be seen that by means of the present invention the attendant has only one operating member to which to attend, and his duties are therefore minimized, because in operating the main steam valve leading to the lubricator, he now automatically at the same time operates the lubricant control valve without, as hitherto, having to attend to two separately-operable valves.

In order to indicate the position of the valves, an indicator-arm 38 secured also to the rock-shaft 33 traverses a scale 39 on which the various positions can be clearly marked. Conveniently, a spring-pressed detent 40 will snap into a recess 41 when the operating member 34 has been moved to a position in which the jockey valve only is open. The attendant is thus given a clear indication when he has moved the operating member to the extent required to open the jockey valve only without the necessity of actually observing the position of the indicator-arm. For the fully-open and fully-closed positions of the valves, the arm 38 can be arranged to engage fixed stops at the ends of the scale member 39.

It is thought unnecessary to refer in further detail to the construction of the lubricating apparatus as a whole, because this is of a well-known type, but it may be mentioned that there is provided, as usual, a plug 42 closing the lubricant-filling orifice; a discharge-control valve 43 for discharging the water from the chamber 11 when the lubricant has all been expelled, and the usual drain and inspection plugs 44 and 45 also for the chamber 11.

I claim:

1. Lubricating apparatus of the kind specified comprising in combination a lubricant chamber, a steam chamber communicating therewith, means to pass condensate from the steam chamber to the lubricant chamber, a steam-inlet control valve for the steam chamber, an outlet control valve for the lubricant chamber, a single operating member, and a valve-timing operative connection between said member and both valves whereby the said steam-inlet control valve is opened prior to the outlet control valve of the lubricant chamber.

2. Lubricating apparatus of the kind specified, comprising in combination a lubricant chamber, a steam chamber communicating therewith, means to pass condensate from the steam chamber to the lubricant chamber, a steam-inlet control valve for the steam chamber, said valve comprising a main valve portion and a jockey valve, an outlet control valve for the lubricant chamber, a single operating member, and coupling means operatively connecting said operating member with the inlet and outlet control valves so that movement of the operating member serves to open the jockey valve prior to the main inlet valve portion and the outlet valve aforesaid. 70
3. Lubricating apparatus of the kind specified, comprising in combination a lubricant chamber, a steam chamber communicating therewith, means to pass condensate from the steam chamber to the lubricant chamber, a steam-inlet control valve for the steam chamber, said valve comprising a main valve portion and a jockey valve, an outlet control valve for the lubricant chamber, a single operating member, and coupling means operatively connecting said operating member with the inlet and outlet control valves so that movement of the operating member serves to open the jockey valve prior to the main inlet valve portion and the outlet valve aforesaid, and subsequently to open the main inlet valve portion and the outlet valve together. 76
4. Lubricating apparatus of the kind specified, comprising in combination a lubricant chamber, a steam chamber communicating therewith, means to pass condensate from the steam chamber to the lubricant chamber, a steam-inlet control valve for the steam chamber, a rotary type outlet control valve for the lubricant chamber, a single operating member comprising a rock-shaft operatively connected with the inlet and outlet control valves in such manner that the rock-shaft and outlet valve are rotatable simultaneously, and a cam actuated by said rock-shaft for controlling the movements of the said steam-inlet control valve. 80
5. Lubricating apparatus of the kind specified, comprising in combination a lubricant chamber, a steam chamber communicating therewith, means to pass condensate from the steam chamber to the lubricant chamber, a steam-inlet control valve for the steam chamber, a rotary type outlet control valve for the lubricant chamber, a single operating member comprising a rock-shaft operatively connected with the inlet and outlet control valves in such manner that the rock-shaft and outlet valve are rotatable simultaneously, and a cam mounted on said rock-shaft to control the movements of the said steam-inlet control valve. 85
6. Lubricating apparatus of the kind specified comprising in combination a lubricant chamber, a steam chamber communicating therewith, means to pass condensate from the steam chamber to the lubricant chamber, a steam-inlet control valve for the steam chamber, a rotary type outlet control valve for the lubricant chamber, a single operating member, and a single valve-operating member comprising a rock-shaft, links operatively connecting the rock-shaft with the outlet control valve whereby the rock-shaft and valve are rotatable together, and a cam actuated by said rock-shaft for controlling the movements of the said steam-inlet control valve. 90
7. Lubricating apparatus of the kind specified comprising in combination a lubricant chamber, a steam chamber communicating therewith, means to pass condensate from the steam chamber to the lubricant chamber, a steam-inlet control valve for the steam chamber, an outlet control valve for the lubricant chamber, and a single operating member coupled with both valves so that they are both movable simultaneously by said member, said outlet valve being of such form that during the first portion of its movement it fails to open whereby the steam inlet valve is opened prior to the said outlet valve. 95
8. Lubricating apparatus of the kind specified, comprising in combination a lubricant chamber, a steam chamber communicating therewith, means to pass condensate from the steam chamber to the lubricant chamber, a steam-inlet control valve for the steam chamber, a rotary type outlet control valve for the lubricant chamber, and a single operating member coupled with both valves so that they are both simultaneously movable thereby, the passages in the valve and valve-casing of the said outlet valve being so dimensioned and arranged that during the first portion of the movement of the valve, it fails to open. 100
9. Lubricating apparatus of the kind specified comprising in combination a lubricant chamber, a steam chamber, a passage connecting the lower end of said steam chamber with the lower end of the lubricant chamber, a steam-inlet control valve for the steam chamber comprising a main valve portion having a passage therethrough, a jockey valve controlling said passage, a rotary type outlet control valve for the lubricant chamber, a single operating member comprising a rock-shaft, a cam on said rock-shaft so shaped as to open the jockey valve during the first portion of its movement and thereafter to open the main valve portion, an operative connection between said rock-shaft and said outlet control valve whereby the latter commences to rotate immediately the rock-shaft is rotated, the passages in the valve and casing of the said outlet control valve being so dimensioned and arranged 105
- 110
- 115
- 120
- 125
- 130

that the valve fails to open during the first movement of the rock-shaft and commences to open at approximately the same time that the main steam inlet valve portion opens.

- 5 10. Lubricating apparatus of the kind specified comprising in combination a lubricant chamber, a steam chamber communicating therewith, means to pass condensate from the steam chamber to the lubricant chamber, a steam inlet control valve for the steam chamber, an outlet control valve for the lubricant chamber and a single operating means which actuates both valves and is set in relation to the valves that the steam valve
10 may when desired by actuation of the single operating means be opened without opening the valve for the lubricant chamber.

In testimony whereof I affix my signature.
